UNITED STATES PATENT OFFICE.

JAMES H. WAGENHORST, OF AKRON, OHIO, ASSIGNEE TO THE B. F. GOODRICH COMPANY, OF NEW YORK, N. Y., A CORPORATION OF NEW YORK

DEMOUNTABLE SPLIT RIM.

1,328,605.

Specification of Letters Patent. Patented Jan. 20, 1920.

Application filed October 4, 1915. Serial No. 32,374.

To all whom it may concern:

Be it known that I, JAMES H. WAGENHORST, a citizen of the United States, residing at Akron, in the county of Summit and State of Ohio, have invented a certain new and useful Improvement in Demountable Split Rims, of which the following is a full, clear, and exact description, reference being had to the accompanying drawings.

10 This invention relates to transversely-split demountable rims, and its object is to provide a structure having a readily engageable and separable interlocking means for the ends of the rim, which shall properly preserve the alignment of said ends, prevent circumferential separation thereof when the rim is expanded by forcing it onto the wheel felly, and prevent collapse of the rim when the latter is demounted and provided with an inflated tire.

Rims of this type are now made principally in the form of a rolled channel with both tire-retaining flanges integral with the rim base, and I have shown my invention as 25 so embodied, although not wholly confining the same to this construction.

My rim is further of the type embodying a plate which bridges the division between the rim ends and forms one of the complementary interlocking or coupling devices, the 30 said devices being preferably permanently mounted on or rigid with the respective rim ends, so that there are no parts in the nature of separate plates or pivoted latches, but 35 the rim constitutes a true single-piece structure with no loose members.

So far as I am aware, the present invention is the first instance of a true single-piece rim having within itself the means 40 for performing all of the functions first above recited.

In a prior Patent No. 1,136,984 of April 27, 1915, I have shown and described, and in a division thereof, patented July 10, 1917, 45 No. 1,228,938, I have claimed a rim of this general type whose base is transversely split on a diagonal line and formed with laterally-interlocking teeth or hooks shown cut in the web or metal of the rim base, together 50 with integral or rigidly-mounted members to prevent relative radial separation of the rim ends in either direction when they are butted together, but the structure there shown is somewhat expensive to manufacture and the rim depends to some extent

on its connection with the wheel felly to prevent a partial lateral disalignment and unlocking of the hooks due to the unbalancing of the tire pressure in the vicinity of the joint, this latter tendency being observed 60 in all diagonally-split rims and requiring special expedients of a cumbersome and unsatisfactory nature in order to overcome it. My present improvements avoid these objections in a simple manner. 65

Of the accompanying drawings,

Figure 1 represents a perspective view of a portion of a transversely-split single-piece rim provided with interlocking means constructed in accordance with my invention. 70

Fig. 2 is a similar view with the rim ends unlocked and radially separated.

Fig. 3 is a plan view with the ends interlocked.

Fig. 4 is a plan view showing a modification. 75

Fig. 5 is a sectional view on the line 5—5 of Fig. 4.

Fig. 6 is a plan view showing another modification. 80

Fig. 7 is a transverse sectional view and Fig. 8 a longitudinal sectional view showing a third modification.

Referring at first to Figs. 1, 2, and 3, 10 indicates a rolled rim with base 11 and tire-bead retaining-flanges 12 made integral. The rim is transversely split, as at 13, preferably at one point only and straight across, that is at right angles or in a plane which either includes or is parallel to the axis of rotation, but this plane may be either radial or inclined to the radius as indicated for example in Fig. 8. A straight-across division of this kind balances the pressure of the tire on both sides of the rim in the vicinity 95 of the joint and prevents any tendency to lateral disalignment of the ends such as is observed in a diagonally-split rim, and when the plane of division is radial as well as straight across, the relatively-deep surface 100 of contact formed by the abutting ends of the integrally flanged rim may to a large extent dispense with other means for preserving radial alignment and preventing the demounted rim from collapsing by the 105 pressure of an inflated tire thereon, although the particular interlocking means herein shown is adapted independently to prevent such radial disalignment.

While any suitable means may be pro- 110

vided for supporting the rim upon and clamping it to the wheel felly, I prefer to employ the Shaw type of circumferentially continuous frusto-conical supporting surfaces affording a continuous wedging engagement between the fixed rim or wheel member and the demountable rim, as described in Patent No. 971,318, 14 being a rib forming one of said rim surfaces and 15 being a roiled depression forming the other rim surface, a portion of the rib 14 being utilized for interlocking purposes in the form of my invention shown in Figs. 1, 2 and 3.

16 is a locking plate bridging the joint 13, on the bottom or inner side of the rim. This plate is most conveniently made as a separate piece, but is preferably rigidly secured to one end of the rim by means such as the rivets 17. For extra security, it may have a dove-tailed lateral projection 18 occupying a similarly-shaped complementary recess 19 formed in the rib 14, but this additional anchoré is not regarded as essential. A dove-tailed projection 20 formed on the plate 16 occupies a similarly-shaped complementary recess 21 formed in the rib 14 on the rim-end opposite the end to which the locking plate is riveted, and when the ends of the rim are butted together the engagement of the member 20 with the walls of the recess 21 preserves the alinement of the rim ends as to relative radial movement in either direction, and also prevents circumferential separation by the hooking action of projection 20 on the shoulder formed by the left-hand face of the recess.

To release the connection, a thin-edged tool such as a screw-driver is inserted between the inner edge of the rib 14 and the adjacent edge of the plate 16 so as relatively to displace the ends of the rim laterally, and when the projection 20 is free, the ends of the rim may be further pried apart both radially and laterally until they clear each other, after which the rim is easily removed from within the tire by progressively pulling it away from the latter, beginning at the end of the rim carrying the locking-plate 16. The application of the rim to a tire is performed in a reverse manner, the rim being first partially collapsed by disalining and overlapping its ends, the end having the recess 21 being applied first, 55 after which the rim is progressively pushed into the tire and the ends finally spread apart, brought into alinement and interlocked with the aid of a screw-driver or other suitable tool.

60 In the modification shown in Figs. 4 and 5, I rivet to one end of the rim a locking-plate 16^a generally similar to the one described, but in this case interlocking with a stud 22 which may be made tubular to ad-

65 mit the passage of the valve-stem of the tire, the stud being provided on one side with a horizontally-projecting lip 23 which overlaps the locking plate, the latter being confined between this lip and the bottom of the rim in order to keep the parts in radial alignment. Plate 16^a is recessed from one side at 24 to embrace the stem of stud 22 and avoid the valve-stem, and is interlocked with said stud or disengaged therefrom by an appropriate lateral movement of the 75 parts.

Fig. 6 shows an arrangement similar to Figs. 4 and 5, except that the stud 22^b is made rectangular or straight-faced, and the recess 24^b correspondingly shaped, and the stud in this case is not hollow. This view also represents the rim flanges 12^b as adapted for the clincher style of tire, whereas the other views represent rims for straight-sided tires, my invention applying to either 85 type.

Figs. 7 and 8 show a locking-stud 22^c in general similar to the one shown in the foregoing modification but occupying a four-sided aperture 24^c in the locking-plate 90 16^c and having a beveled rear face 25 up which the locking-plate rides when the rim ends are being pried apart. Fig. 7 shows a mode of mounting the rim 10 on the fixed rim 26 of the felly 27 and securing it 95 by means of bolts and clips such as 27, 28.

Fig. 8 shows one of the rivets 17^c for anchoring the locking-plate formed with a head adapted to enter a suitable recess in the fixed rim and act as a driving lug. 100

It will be understood that various other modifications could be made without departing from the spirit of my invention.

I claim:

1. A single-piece demountable tire-carrying rim transversely split in a plane substantially parallel with its axis of rotation, and having rigidly-mounted interlocking and alining devices, said devices arranged to prevent circumferential separation of the 110 rim ends and adapted to preserve the radial alinement of said ends as to relative movement in either direction when the ends are butted together.

2. A demountable tire-carrying rim transversely split and provided on the bottom or inner side of the rim base with rigidly-mounted members which interlock by relative lateral movement of the rim ends to prevent their circumferential separation, one 120 of said members bridging the joint between the rim ends.

3. A demountable tire-carrying rim transversely split and having a locking shoulder near one rim end, and a locking plate rigidly mounted on the other rim end and overlapping the joint, said plate having hooked engagement with said shoulder by relative lateral movement of the rim ends to prevent circumferential separation of the latter. 130

4. A demountable tire-carrying rim transversely split and formed on its inner side with a circumferential rim-supporting rib, said rib being provided with a recess near one end of the rim, and a locking plate adapted to enter said recess by lateral movement for interlocking the rim ends.

5. A demountable tire-carrying rim transversely split and formed on its inner side with a rim-supporting rib which is recessed near one end, together with a locking plate rigidly mounted on the other end of the rim and provided with a lateral projection for entering said recess by relative lateral movement of the rim ends to lock the latter against circumferential separation.

6. A demountable tire-carrying rim transversely split and having its end portions provided with rigidly-mounted coupling members which interlock the rim ends as to both circumferential and radial separation and which engage and disengage by relative lateral movement of the rim ends, one of said members being a plate which bridges the joint.

7. A demountable tire-carrying rim transversely split and formed on its inner side

with a circumferential rim-supporting rib provided near one end with an under-cut recess, and a locking plate rigidly attached 30 to the other end of the rim and having a complementary lateral locking projection adapted to enter said recess.

8. A demountable tire-carrying rim transversely split substantially at right-angles 35 to the sides and having its end portions provided respectively with an undercut locking member and a rigidly-mounted locking plate bridging the joint and adapted for hooked engagement with said member. 40

9. The combination with a transversely split tire-carrying rim, of a locking device for securing the rim-ends together, comprising members rigid on the rim-ends respectively, one of said members having an opening therein for receiving the other member, said members having interfitting dove-tailed edges which secure the rim-ends against relative radial movement when the rim is subjected to contracting pressure and when it 50 is subjected to expanding pressure.

In testimony whereof, I hereunto affix my signature.

JAMES H. WAGENHORST.
